UNITED STATES PATENT OFFICE.

MAURICE ROSENBERG, OF BROOKLYN, NEW YORK, ASSIGNOR TO SHAPIRO & ARONSON, INC., OF NEW YORK, N. Y., A CORPORATION OF NEW YORK.

DESIGN FOR AN ARM FOR LIGHTING-FIXTURES.

52,966.

Specification for Design.

Patented Feb. 4, 1919.

Application filed April 23, 1918. Serial No. 230,370. Term of patent 3½ years.

To all whom it may concern:

Be it known that I, MAURICE ROSENBERG, a citizen of the United States, residing at Brooklyn, in the county of Kings and State of New York, have invented a new, original, and ornamental Design for an Arm for Lighting-Fixtures, of which the following is a specification, reference being had to the accompanying drawing, forming part thereof.

Figure 1 is a front elevation of an arm for lighting fixtures, showing one half of the ornamental design, it being apparent that the other half is a duplication thereof.

Fig. 2 is a side elevation of the same.

I claim:

The ornamental design for an arm for lighting fixtures, as shown.

MAURICE ROSENBERG.
